UNITED STATES PATENT OFFICE.

JOSEPH W. HOBSON, OF BAYONNE, NEW JERSEY.

DUMPING-WAGON.

No. 894,003.

Specification of Letters Patent.

Patented July 21, 1908.

Application filed June 6, 1907. Serial No. 377,556.

To all whom it may concern:

Be it known that I, JOSEPH W. HOBSON, a citizen of the United States, and resident of Bayonne, in the county of Hudson and State 5 of New Jersey, have invented an Improvement in Dumping-Wagons, of which the following is a specification.

My invention is an improvement in dumping wagons, and consists in certain novel constructions and combinations of parts as will 10 be hereinafter described and claimed.

In the drawing, Figure 1 is a side view of a wagon embodying my invention, the wheels on the one side being removed. Fig. 2 is a 15 detail sectional view illustrating two of the bottom sections; and Fig. 3 is a bottom plan view of one of the bottom sections. Fig. 4 is a detail section illustrating the bearings for the trunnions of the sections, and Fig. 5 is a 20 detail section illustrating a somewhat different arrangement of bearing.

The vehicle may in general respects be of ordinary construction, the novelty consisting in the construction of the body whereby to 25 secure the dumping operation, and in the means for operating the dumping parts, as will be more fully described.

As shown, the body has sides A, and is provided at the base thereof with bearings at B, 30 for the trunnions C' and C² of the bottom sections C, whose plates C³ are secured near one edge upon the cross bars C⁴, providing the main or body wing of the plates C³ and the narrow overlapping extension C⁵ as best 35 shown in Figs. 2 and 3 of the drawing.

The sections C are pivoted by the journaling of their trunnions C' and C² in the bearings B of the sides A of the wagon body, and may be tilted to the full line position shown 40 in Fig. 1, and illustrated in Fig. 2, in which they close the bottom of the wagon body, and in which the overlapping extension C⁵ of each plate overlaps the swinging edge of the adjacent plate and aids in securing a tight bottom for the wagon, or such plates may be adjusted to the dotted line position indicated in Fig. 1 to dump the contents of the wagon body as will be understood from Fig. 1.

Each section C is provided with a crank 50 arm D alongside the wagon body and preferably secured to the trunnion C² so the several crank arms D will project upwardly alongside the body when the sections are adjusted to close the bottom of the body. The several 55 crank arms D are connected at their swinging ends by a connecting rod E which is moved

longitudinally toward the front of the wagon to the position shown in Fig. 1, by suitable means, preferably a chain F connected with the front end of the rod E and arranged to be 60 wound on or unwound from a suitable drum in order to secure the parts in the full line position shown in Fig. 1, or to release the sections so they may be dumped by the weight of the load thereon as may be desired 65 in the use of the invention.

In practice, the plates C³ may be of steel, about $\frac{3}{16}$ ths of an inch thick by 14 inches wide, more or less, bolted or riveted to the bars or shafts C⁴, which may be 1 $\frac{1}{4}$ inch 70 square, more or less, with the ends suitably rounded to form the trunnions bearing in the sides of the body. It will be noticed that the bottom sections extend transversely and are pivoted eccentrically so they will dump by 75 gravity when released.

While the invention has been shown embodied in a four-wheel vehicle, it is manifest it may be used on two wheel carts where so desired.

In journaling the trunnions or journals of the sections they may be journaled directly in the sides A and in the upright wings of the angle sills as best shown in Fig. 4, or boxes 80 may be provided on the under sides of the 85 base or flat wings of the angle sills and have the bearings, as shown in Fig. 5 of the drawings.

Where desired the sills and side boards may be of wood. Manifestly any suitable 90 material may be employed in the construction of the different parts of the device.

I claim:

1. The combination with a wagon body, of angle irons extending along the outer sides 95 thereof adjacent to the bottom and having upright wings and laterally outwardly extending wings at the lower ends of the upright wings, tilting bottom sections having trunnions journaled in the upright wings and extending above the lateral wings, said bottom sections having crank arms, and operating devices connected with the crank arms, substantially as set forth.

2. The combination of a wagon body, angle irons extending along the sides thereof adjacent to the bottom of the body and having upright sills and laterally extending sills, tilting bottom sections journaled in connection with the said angle irons, and means for 105 operating the bottom sections, substantially 110 as set forth.

3. The combination of a wagon body, angle irons secured thereto at the bottom of the body and having upright wings and laterally extending wings, and tilting bottom sections having trunnions journaled in the upright wings of the angle irons and resting on the lateral wings thereof, and means for operat-

ing the tilting bottom sections, substantially as set forth.

JOSEPH W. HOBSON.
